(57) **CLAIM**

We claim the ornamental design for a handle for a child swing, as shown and described.

DESCRIPTION

FIG. 1 is a front perspective view of a handle for a child swing according to our new design;

FIG. 2 is an enlarged front view thereof;

FIG. 3 is an enlarged back view thereof;

FIG. 4 is an enlarged left side view thereof;

FIG. 5 is an enlarged right side view thereof;

FIG. 6 is an enlarged top view thereof; and,

FIG. 7 is an enlarged bottom view thereof.

The broken lines shown in the drawing are for illustrative purposes only and form no part of the claimed design.
